HENRY S. VAUGHN, OF LOUISVILLE, KENTUCKY.

ROTARY PUMP.

1,096,804.

Specification of Letters Patent. Patented May 12, 1914.

Application filed July 3, 1913. Serial No. 777,290.

To all whom it may concern:

Be it known that I, SAMUEL W. EGGLETON, a citizen of the United States, residing at Louisville, in the county of Jefferson and 5 State of Kentucky, have invented new and useful Improvements in Rotary Pumps, of which the following is a specification.

This invention relates to rotary pumps and an object to be attained is the production 10 of a pump that will be efficient in operation, economical in construction, and durable in service.

With this and other objects in view the invention consists of the novel construction 15 and arrangement of parts set forth, and illustrated in the accompanying drawings which form a part of this specification, in which is set forth an embodiment of the invention, but it is to be understood that 20 changes, variations and modifications may be resorted to that come within the scope of the claims appended hereunto.

In the drawings, in which like reference characters indicate like parts in the different 25 views; Figure 1, is a side elevation of an embodiment of the invention; Fig. 2, is a central vertical section; Fig. 3, an elevation of the inside of the casing, on a reduced scale; Fig. 4, an elevation of the inside of 30 the cover, on a reduced scale; Fig. 5, a view of the face of the rotor; Fig. 6, a view of the back of the rotor; Fig. 7, a plan view of the pump; Fig. 8, a side elevation of the valve; Fig. 9, a perspective of the bushing.

35 Referring to the drawings —1— indicates a circular, cup-shaped, casing having an outer chamber —2— and an inner chamber —3— of less diameter and having a flange —4— around the open end thereof affording means whereon a cover —5— may be secured by suitable means such as bolts —6—. A bearing —7—, in the closed end 40 of the casing, provides for the passage of a shaft —20—, a stuffing box 8 being provided on the exterior of the bearing. Within the chamber 3 is disposed a concentric ring —9— spaced from the wall of the chamber and of suitable height to provide a bearing therebetween for rings on a rotor 45 to be hereinafter described. Midway between the ring 9 and the wall of the cas-

ing are induction and eduction ports —10— and —11— spaced a suitable distance apart. An arc-shaped discharge block —12— occupies the space between these ports. The 55 inner face —13— of the chamber 3 and the outer side —14— of the ring 9 are tapered toward the bottom of the casing, as are the sides of the discharge block 12. A rotor, or impeller, —15— is provided that fits 60 within the chamber 3. On the face of the rotor are concentric rings —16— and —17— spaced apart to provide a raceway —18—. The sides of the rings 16 and 17 are tapered to allow them to seat between the side 14 of 65 the ring 9 and the wall of the chamber, and to permit the discharge block to seat within the raceway. The rotor is further provided with a hub that is bored out for the reception of a shaft —20—, the rotor being secured thereon by suitable means such as a key —21—. A plurality of valves, or interceptors, —22— are disposed centrally in the course of the raceway, and are adapted to be oscillated in a plane parallel with the 70 axis of the rotor. The body —23— of the valve is larger in diameter than the width of the raceway, encroaching respectively upon the rings 16 and 17, and has a tapered base —24—, a stem —25—, the end of the 80 stem being adapted, as by having a squared portion —26—, to receive a dog —35—. Extending from the face of the valve is a sector shaped portion —27—, that, in the open position of the valve, lies within the 85 confines of the outer ring 16 (as shown at 27 in Fig. 5.) and at other times lies across the raceway (as shown at 27' in Fig. 5). In the side of the ring 17, in proximity to each valve is a recess —28— in which is 90 located a stop block —29— that extends across the face of the valve into position to serve as an abutment for the sector 27. The valve parts subject to wear require occasional replacement. To facilitate repairs I 95 provide a bushing —30— having a central perforation —31— and a tapered seat —32— adapting it for the reception of the valve. The bushing extends through the rotor and is secured in place by suitable means such 100 as dowel screw —33—. The inner end of the bushing is shaped to conform to the

raceway in the rotor, and the other end has a projection —34— that serves to hold the dog 35 off from the back of the rotor. The dog 35 is provided with diverging arms 5 —36— and —36'— and is secured on the squared portion 26 of the valve stem by suitable means such as a set screw —37—. Pins —38— are so positioned on the back of the rotor as to limit the throw of the dogs, the arrangement being such that the dog strikes the pin at the moment the sector 27 assumes the desired position.

On the inner side of the cover 5 an arc-shaped block —39— is secured in such relationship to the discharge block 12, on the casing, that as the rotor turns, in the direction of the arrow, an arm —36— on the dog attached to one of the valves, will contact with the end —40— thereof, turning the valve until the sector 27 retires within the limits of the ring 16 into position to pass over the discharge block 12, the arm 36 contacting with a pin 38 and the side of the arm sliding over the block 39; as the end of the arm 36 escapes from the block 39 the arm 36' is in position to strike an angular extension —41—, on a semi-circular member —42—, shifting the valve in the opposite direction, bringing the arm 36' 20 against a pin 38, and placing the sector 27 across the raceway, the side of the dog will lie in contact with the circle 42 holding the valve steady during the continued movement of the rotor. The valve opening and closing blocks 39 and 42 are removably attached to the cover in order that they may readily be replaced in case of wear. A bearing —43— in the cover is adapted to receive a ball-bearing thrust member —44—. 25 A plate —45— covering the outer end of the bearing is provided with a screw-threaded aperture through which a screw —46— extends that is adapted to adjust the position of the thrust bearing 44. Hand-holes —47— and —49— having closures —48— and —50— located respectively in the cover and casing, and being positioned opposite each other, provide access to the valves and bushings. By removing the closure 48 a tool may be introduced through the manhole 47, the set screw 37 loosened, the dog 35 removed from the valve stem, the dowel screw 33 taken out, then by exerting pressure from the other side, through the handhole 49 the bushing 30, with contained valve, may be removed.

The operation may now be understood. Starting from the position shown in the drawings, the rotor turning in the direction of the arrow, as the sector 27 clears the block 12, the arm 36 of the dog clears the block 39, the arm 36' contacts with extension 41 turning the valve and placing the

sector 27 across the raceway 18, this impounds the fluid between the sector just shifted and the preceding one, the movement of the valve creates a partial vacuum in its rear that draws the fluid through the induction port. As a valve approaches the eduction port an arm 36 on a dog comes into contact with the end of the opening block 39 and the sector is shifted from the position across the raceway into position to pass over the discharge block, and the fluid that was impounded between it and the succeeding valve will be forced out through the eduction port. This sequence of movements recurs constantly. It will be observed that the valves divide the raceway into three parts one of which is constantly drawing fluid through the induction port, another carrying the impounded fluid around the circle and the third is forcing fluid out through the eduction port, this results in a constant flow of fluid.

It is obvious that the pump may be mounted in any desired position, vertical or horizontal, and driven by any suitable means, direct coupled to an electric motor, a turbine engine or otherwise. I have illustrated it as mounted on a base —51— and having a pulley —52— secured on the shaft 20, providing thereby for driving it by means of a belt from any suitable source of power.

Having thus described my invention so that any one skilled in the art pertaining thereto may make and use the same

I claim:

1. In a pump of the class described, a cup-shaped casing having induction and eduction ports, a rotor comprising a disk having an annular passage in the face thereof, a block between said ports and entering said raceway, a plurality of interceptors disposed about said raceway and extending through said rotor, and means associated with the back of the casing for shifting said interceptors.

2. In a pump of the class described, a cup-shaped casing having induction and eduction ports, a rotor comprising a disk having an annular passage in the face thereof, said ports opening in the raceway, a block between said ports entering the raceway, interceptors disposed around said raceway and means for shifting said interceptors to enable them to pass said block.

3. In a pump, a cup-shaped casing having induction and eduction ports, a rotor comprising a disk having an annular raceway in the face thereof, said ports opening into said raceway, a block between said ports obstructing said raceway, interceptors seated in said raceway and extending through said rotor and means associated therewith for

shifting the same to enable them to pass said block.

4. In a pump, a cup-shaped casing, a closure therefor, a rotor comprising a disk having an annular passage for fluid, the casing having ports opening into said passage, a block between said ports and entering said passage, interceptors seated in said passage and extending through the rotor, means associated with said closure for shifting said interceptors and for holding them immovable during a portion of a rotation.

5. A cup-shaped casing having induction and eduction ports, a closure therefor, a rotor comprising a disk having an annular passage in the face thereof, a block between said ports entering said passage, interceptors seated in said passage, stems on said interceptors extending through the rotor, dogs on the ends of said stems, and means associated with said closure adapted to engage said dogs and shift the interceptors.

6. A casing having induction and eduction ports, a closure for the casing, a rotor having a passage for fluid, a block between said ports, interceptors around said passage, a plurality of removable bushings extending through said rotor and in the course of said passage, interceptors mounted in said bushings, dogs connected with said interceptors and means associated with said closure adapted to engage said dogs and shift said interceptors.

7. A cup-shaped casing having induction and eduction ports, a closure for the casing, a rotor comprising a disk having an annular passage in the face thereof, a block between said ports and entering said passage, a plurality of interceptors seated in said passage, stems on said interceptors extending through said rotor, dogs on said stems, a block on said closure adapted to shift said interceptors from said passage and a second block adapted to return said interceptors to the passage.

8. A casing having induction and eduction ports, a closure for the casing, a rotor having a passage for fluid, a plurality of interceptors disposed in said passage, bushings in which said interceptors are seated, stems on said interceptors extending through the rotor, dogs on said stems, blocks on said closure adapted to engage said dogs to shift said interceptors into and out of said passage.

9. A casing having induction and eduction ports, a closure for said casing, a rotor having a circular passage for fluid, a block between said ports and adapted to obstruct said passage, a plurality of interceptors disposed in said passage, removable bushings in which said interceptors are adapted to be seated, stems on said interceptors extending

through said rotor, dogs on said stems, block on said closure for engaging said dogs to shift said interceptors, a shaft on which said rotor is mounted, a thrust bearing in said closure, and means for adjusting said bearing.

10. A cup-shaped casing having induction and eduction ports, a rotor comprising a disk, spaced concentric rings on the face thereof, a block between said ports entering the space between said rings, interceptors seated between said rings, stems on said interceptors extending through said rotor, dogs on said stems and means adapted to engage said dogs to shift said interceptors.

11. A cup-shaped casing having inner and outer chambers, a rotor seated in said inner chamber, spaced concentric rings on the face of said rotor, said casing having ports opening into the space between said rings, a block between said ports obstructing said space, interceptors seated between said rings, stems on said interceptors positioned in said outer chamber for shifting said interceptors.

12. A cup-shaped casing having inner and outer chambers, a rotor seated in said inner chamber, spaced concentric rings on the face of said rotor, said casing having ports opening into the space between said rings, a block between said ports obstructing said space, interceptors seated between said rings, stems on said interceptors extending through said rotor, dogs on said stems, a closure for said casing, blocks on said closure adapted to shift said interceptors, and a member thereon adapted to hold said interceptors against displacement during a portion of a rotation.

13. A casing having inner and outer chambers, a rotor seated in said inner chamber, spaced concentric rings on the face of said rotor, said casing provided with ports opening into the space between said rings, a plurality of interceptors disposed between said rings, removable bushings adapted to receive said interceptors and means positioned in said outer chamber for operating said interceptors.

14. A casing having inner and outer chambers, a rotor seated in said inner chamber, spaced concentric rings on the face of said rotor, said casing provided with ports opening into the space between said rings, a plurality of removable bushings disposed between said rings, interceptors seated in said bushings, stems on said interceptors extending through said rotor, dogs on said stems, a closure for said casing, means attached to said closure adapted to engage said dogs and shift said interceptors, a shaft on which said rotor is mounted and an adjustable thrust bearing therefor.

15. A casing having an inner and an outer chamber, a rotor seated in said inner cham-

ber, spaced concentric rings on the face of said rotor, said casing provided with ports opening into the space between said rings, a block between said ports extending into said space, a plurality of intercepters disposed between said rings, removable bushings adapted to receive said intercepters, means positioned in said outer chamber for oper-

ating said intercepters, a shaft on which said rotor is mounted and an adjustable thrust bearing for said shaft.
